(57) **CLAIM**

The ornamental design for an ostomy pouch, as shown and described.

DESCRIPTION

FIG. 1 is a perspective view of an ostomy pouch, showing my new design;

FIG. 2 is an enlarged view of a portion thereof as shown within a dashed circle in FIG. 1;

FIG. 3 is a front view thereof;

FIG. 4 is a top view thereof;

FIG. 5 is an enlarged view of a portion thereof as shown within a dashed circle in FIG. 4;

FIG. 6 is a left side view thereof, the right side being a mirror image thereof;

FIG. 7 is an enlarged view of a portion thereof as shown within a dashed circle in FIG. 6;

FIG. 8 is a rear view thereof;

FIG. 9 is a bottom view thereof; and,

FIG. 10 is an enlarged view of a portion thereof as shown within a dashed circle in FIG. 9.

The broken lines shown in FIGS. 1-10 illustrate portions of the ostomy pouch that form no part of the claimed design. Dashed circles indicate portions of the ostomy pouch shown in enlarged views in other figures and form no part of the claimed design.

Dash-dot boundary lines indicate boundary lines and form no part of the claimed design.
